UNITED STATES PATENT OFFICE.

CHARLES B. PERRY, OF HERKIMER, NEW YORK.

DESIGN FOR A SHOE.

No. 38,150.

Specification for Design.

Patented July 31, 1906.

Application filed May 31, 1906. Serial No. 319,656. Term of patent 14 years.

To all whom it may concern:

Be it known that I, CHARLES B. PERRY, a citizen of the United States, residing at Herkimer, in the county of Herkimer and State of New York, have invented a new, original, and ornamental Design for Shoes, of which the following is a specification.

In the accompanying drawings, forming part of this specification, Figure 1 is a perspective view of a shoe, showing my new design. Fig. 2 is a top plan view of the same.

I claim—

The ornamental design for a shoe as shown.

CHARLES B. PERRY.
